UNITED STATES PATENT OFFICE.

JOHN J. BERRIGAN, OF CHICAGO, ILLINOIS, ASSIGNOR OF ONE-THIRD TO JOHN B. BERRIGAN AND ONE-THIRD TO KATHERYNE P. MALON, BOTH OF CHICAGO, ILLINOIS.

PRESS.

Application filed August 28, 1924. Serial No. 734,558.

To all whom it may concern:

Be it known that I, JOHN J. BERRIGAN, a citizen of the United States, residing at Chicago, in the county of Cook and State of Illinois, have invented a certain new and useful Improvement in Presses, of which the following is a specification.

This invention relates to a press, particularly to a hydraulic press. It has for one object to provide means whereby the contents of the press may be readily and positively discharged, particularly after the pressing operation has been completed. Another object is to provide in a press means whereby the pressed cake even though extremely hard and difficult to separate may be positively and easily discharged. Other objects will appear from time to time throughout the specification and claims.

20 My invention is illustrated more or less diagrammatically in the accompanying drawings, wherein:

Figure 1 is a side elevation;

Figure 2 is a plan view with parts in section;

Figure 3 is a vertical cross section on line 3-3 of Figure 1.

Like parts are indicated by like characters throughout.

30 The press is carried preferably on two pairs of supporting legs A A, which legs are joined by channel members B B. The channels are bent outwardly as at B¹ B¹. At one end of the press is a pressure cylinder C within which is located a piston C¹. Supported from this piston on a rod C² is a movable platen C³. This platen is adapted to slide upon and to be supported by channels B B and is wide enough so as to pass 40 over the widened portion B¹ without falling through.

At the opposite end is a pressure cylinder D having in it a piston D¹. A second moving platen D² is carried from the piston D¹ by means of the rod D³. The pressure cylinder D is preferably of sufficient length to permit the platen D² to be moved into the press fully to complete the pressing operation in one pressing movement. The two 50 pressure cylinders are preferably hydraulic. Hydraulic pressure may be supplied to them in any suitable manner through any suitable connections. These details are not shown in detail as they form no part of the present invention.

Mounted between the two platens and resting upon the channels B are a plurality of partition plates E. These plates when the press is to be filled are normally put in the position shown in Figures 1 and 2, being spaced apart from each other. They are of such width that when moved over the widened portion D¹, they will fall through it, but when placed as shown in Figures 1 and 2 they rest on the channels as shown in detail in Figure 3 and are supported by these channels.

Surrounding the press is a covering casing made up preferably of fixed sides F F, a movable bottom F¹, and a movable top F². The bottom F¹ may be made of a number of plates pivoted at G for swinging movement and fastened by a latch G¹. The top F² may be similarly made of a number of plates pivoted at G² and fastened closed by latches G³. The bottom covering F¹ may extend under the widened portion B¹ or it may be omitted from this part of the press, and the top covering F² may extend over this portion or it may be omitted. The detailed construction of the casing is not shown as its details form no part of the present invention, and they might be considerably varied. A perforated bottom might be used and many means might be provided for permitting liquid from the contents of the press to escape, but my invention is not limited to any particular form of the casing construction.

H H are perforations through the side walls F of the channels B and they are adapted to receive rods or shafts H¹.

Although I have shown an operative device, still it will be obvious that many changes might be made in size, shape and arrangement of parts without departing materially from the spirit of my invention; and I wish, therefore, that my showing be taken as in a sense diagrammatic. Particularly I have shown one form of locking device for holding the top and bottom in position. This is shown in Figure 3 and has been omitted in the other two figures for purposes of clearness. However, any such locking device might be used without departing materially from the spirit of my invention.

The use and operation of my invention are as follows:

When the press is to be used, the movable

platens C³ is moved forward to the position indicated at dotted lines in Figure 2 at X and one or more holding devices such as the rods H¹ are inserted, thus holding the platen 5 against outward movement. Any suitable number of plates is put into position as shown and the bottom of the press is held closed. It is then filled with material to be 10 pressed and pressure is applied on the moving platen. It moves the contents of the press, together with the partition plates toward the now fixed platen and this movement is continued until the pressing is complete.

15 The next step in the movement is to discharge the contents of the press. After this the rods H^1 are removed and pressure is again applied on the side of the pressing plate, and this moves the entire contents of
20 the press and the platen C^3 laterally to the left as shown in Figures 1 and 2. The platen C^3 moves over the widened part where the channels are spread and back to its initial position. The partition plates are not of
25 sufficient width to do this and as they come over the widened part, they fall through the channels and from the press, and thus, of course, carry the contents of the press with them.

30 Frequently it will be found that the
pressed cake will fall freely from the parti-
tion plates, but if it is particularly hard and
difficult to deal with it can be knocked or
otherwise positively removed from the
35 plates. By this means the contents of the
press no matter how hard, sticky or tena-
cious it may be, can readily be discharged
from the press and removed from the parti-
tion plates.

40 As soon as the pressed contents have been discharged the platen D² is withdrawn. The platen C³ is moved again to the dotted line position and secured in that position, and the same partitions or additional ones are put into place and the press may again be filled and operated. Thus the operation of discharging the press is rendered positive and extremely rapid and the entire apparatus is not put out of productive operation while discharge takes place and while the material is being removed from the plates.

I claim:

- 55 1. In a press, partitions within said press mounted for movement, and supports which normally hold said partitions during pressing, said supports shaped throughout a portion of their length so as to permit the contents of said press and said partitions to fall.

60 2. In a hydraulic press, a plurality of partitions and supports along which said partitions are adapted to move, said supports being spaced away from each other, throughout a portion of their length, a dis-

tance greater than the width of said partitions so as to cause the partitions to fall therethrough when moved over said spaced away portions.

3. In a press, a plurality of partitions and supports along which said partitions are adapted to move and means for moving them, said supports being spaced away from each other, throughout a portion of their length, a distance greater than the width of said partitions so as to cause the partitions to fall therethrough when moved over said spaced away portions. 70 75

4. In a press members adapted partially to enclose the contents of said press, said members mounted for movement and a support which normally holds said members during pressing, said support shaped throughout a part of its length so as to permit the contents of said press and said members to fall from the press, in combination with a moving member adapted during pressing to be held in position to prevent discharge from the press and adapted after pressing to be moved so as to permit discharge from the press. 85 90

5. In a press, members adapted partially to enclose the contents of said press, said members mounted for movement and a support which normally holds said members during pressing, and means for moving said members, said support shaped throughout a part of its length so as to permit the contents of said press and said members to fall from the press, in combination with a moving member adapted during pressing to be held in position to prevent discharge from the press and adapted after pressing to be moved so as to permit discharge from the press. 95 100 105

6. In a press, partitions within said press mounted for movement, and supports which normally hold said partitions during pressing, said supports shaped throughout a portion of their length so as to permit the contents of said press and said partitions to fall from said press, in combination with a moving member adapted during pressing to be held in position to prevent discharge from the press and adapted after pressing to be moved so as to permit discharge from the press. 115

7. In a press, a plurality of partitions and supports along which said partitions are adapted to move, said supports being spaced away from each other, throughout a portion of their length, a distance greater than the width of said partitions so as to cause the partitions to fall therethrough when moved over said spaced away portions, in combination with a moving member adapted during pressing to be held in position to prevent discharge from the press and adapted after pressing to be moved so as to permit discharge from the press. 120 125 130

8. In a hydraulic press, a plurality of partitions and supports along which said partitions are adapted to move and means for moving them, said supports being spaced away from each other, throughout a portion of their length, a distance greater than the width of said partitions so as to cause the partitions to fall therethrough when moved over said spaced away portions, in combination with a moving member adapted during pressing to be held in position to prevent discharge from the press and adapted after pressing to be moved so as to permit discharge from the press.
- 15 9. In a hydraulic press, a pair of movable platens and a plurality of partitions between them, said platens and partitions supported upon guide members, one of said platens adapted normally to be held stationary during pressing, and adapted when pressing is complete to be moved along the guide members, said guide members spaced apart a distance greater than the width of the partition so that when moved over said space the partitions and contents of the press fall through.
- 20 10. In a hydraulic press, a pair of movable platens and a plurality of partitions between them, said platens and partitions supported upon lateral guide members, one of said platens adapted normally to be held

stationary during pressing, and adapted when pressing is complete to be moved along the guide members with the partitions and the contents of the press, said guide members spaced apart a distance greater than the width of the partition so that when moved over said space the partitions and contents of the press fall through.

35 11. In a horizontal press partitions within said press mounted for generally horizontal movement and supports which normally hold said partitions during pressing, said supports shaped throughout a portion of their length so as to permit the contents of said press and said partitions to fall from said press.

40 12. In a horizontal press, a plurality of partitions and supports along which said partitions are adapted to move in a generally horizontal direction and means for moving them, said supports being spaced away from each other, throughout a portion of their length, a distance greater than the width of said partitions so as to cause the partitions to fall therethrough when moved over said spaced away portions.

50 Signed at Chicago, county of Cook and State of Illinois, this 23 day of August, 1924.

55 JOHN J. BERRIGAN.
